UNITED STATES PATENT OFFICE

2,589,481

FOLDABLE WALLET

Frank G. Dobbs and Stephan H. Dobbs,
New York, N. Y.

Application December 13, 1950, Serial No. 200,590

2 Claims. (Cl. 150—38)

1

The invention relates to foldable receptacles, and relates more particularly to foldable receptacles of the type commonly referred to as wallets.

Desirable features of wallets include pleasant appearance, easy folding, and stiffness of the folded wallet to preserve the contents intact, and these features are generally found in wallets now in use. However, wallets heretofore made were deficient in that the so-called stay, namely the connecting piece between the inner flaps of the wallet, causes crumpling of the contents of the wallet after protracted use.

The reason for this unsatisfactory working of present wallets is found in the fact that the stay is either fixed to both pockets, or slides relative to one of them by being freely inserted there into. The fixed stay will, upon folding of the wallet, bulge inwardly, and thus may cause damage to the contents. The freely movable stay, on the other hand, after a certain period of use will not slide freely enough so that after a while the stay will not return to its assigned position in the pocket upon folding and will instead form an inward bulge between the pockets. This, in turn, will cause crumpling of the contents.

It is therefore among the objects of the invention to provide a wallet that will retain without damage the contents upon folding of the wallet. This is accomplished, in accordance with the invention, by making the stay movable while detachably fastening it to the wallet exterior after folding.

Further objects and advantages of the invention will be set forth in part in the following specification and in part will be obvious therefrom without being specifically referred to, the same being realized and attained as pointed out in the claims hereof.

In the accompanying drawings,

Fig. 1 is an elevational view, illustrating the interior of a wallet in unfolded position, some portions of the pockets having been broken away to expose parts in back thereof;

Fig. 2 is a sectional view taken on line 2—2 of Fig. 1;

Fig. 3 is an elevational view showing the exterior of the folded wallet;

Fig. 4 is a sectional view taken on line 4—4 of Fig. 3, showing the folded wallet having only a few contents (the contents not being shown); and

Fig. 5 is a sectional view similar to Fig. 4, but illustrating the wallet thickened due to voluminous contents (the contents not being shown).

In carrying the invention into effect in one of the embodiments which has been selected for illustration in the accompanying drawings and for description in this specification, and referring now particularly to Figs. 1—3, there is provided a

2

wallet generally indicated at 11. The wallet 11 comprises an outer wall 12 being foldable about the middle or midway section 13 between an open position (Fig. 1) and a closed position (Fig. 3).

5 In front of the outer wall there are disposed two frontal flaps, a left flap 14 and a right flap 16 that are connected to the outer wall along their lower and their outer side edges, for instance by a stitching seam 17; however, the flaps 14 and 16, instead, may be connected to the outer wall by any other suitable means and operations, such as, for instance, by sealing.

The material of the wallet and its component parts may be either natural leather, or 15 artificial leather, or plastic for instance of the thermoplastic type, or any other suitable conventional material.

The flaps 14 and 16 are spaced from each other for a gap 18 adjacent the midway section 13, to 20 permit free relative movement thereof during folding and unfolding. The frontal flaps 14 and 16 are, with the exception of the seam 17, separated from the outer wall, forming therewith along the outer wall a left pocket 21 and a right 25 pocket 22. An intermediate flap 23 may be provided between the flaps 16 and the outer wall 12, forming with the flap 16 a sleeve or pocket 24 closed all around except being open at 26 towards the gap 18. A flap portion 27 is disposed between the flap 14 and the outer wall 12 forming therewith a sleeve or pocket 28 that is open at 29 towards the gap 18 and closed throughout the remainder.

There is provided a stay, generally indicated at 31, that includes the flap portion 27 and is either connected thereto, or integral therewith as shown in Fig. 1. The stay 31 furthermore includes a wide portion 32 that is only slightly narrower than the flap portion 27 and bridges the gap 18 40 and extends to the interior of the pocket 24. The stay 31, finally, also has a narrow, elongated portion 33 that may be connected to the wide portion 32 or be integral therewith, and extends from the free end 34 thereof towards the outer 45 right hand side edge of the wallet.

It will be understood, that further flaps and pockets or other compartments may be provided in said wallet, without departing from the spirit and scope of the invention, the instant simplified construction being described only for the purpose of clarification; conversely, the wallet may have fewer parts, such as pockets or compartments, than those shown; likewise, the terms "right" and "left" and similar terms are used herein only in an explanatory and not in any limiting sense.

The elongated portion 33 extends to the interior of the wallet from the pocket 24, through a slot 34 in the flap 23 and through a slot 36 in the 55 outer wall 12. Near its terminal at the wallet 60 outer wall 12.

exterior, the elongated portion 33 carries one part 37 of a fastening device, such as a snap fastener, the second snap fastener part 38 being mounted on the outside of the outer wall 12 near the other end thereof.

This stay 31—that comprises the flap portion 27, the wide portion 32 and the elongated portion 33—extends from the left end where it is connected by the seam 17 to the outer wall 12, towards the right end of the wallet and there beyond the confines thereof. The bottom of the flap portion 27 is fastened, by the seam 17, to the edge of the outer wall, and is therefore substantially immovable relative to the outer wall and to the opposite pocket 24. The remainder of the stay, however, namely the wide portion 32 and the elongated portion 33, are movable relative to the outer wall and also relative to the pocket 24, by the sliding of said wide portion 32 in said pocket 24, as well as the sliding of the elongated portion 33 in the slots 34 and 36.

The overall length of the stay 31, as best shown in Fig. 2, measured from the left end to the center of the snap fastener 37, is indicated at "b"; it will be appreciated that "b" indicates the length of the straight stay, though in the illustration of Fig. 2 the stay 31 is shown bent at certain places. The distance from the left end to the center of the other part 38 of the snap fastener is indicated at "a." The dimensions of the distances "a" and "b" are so arranged that when the wallet is folded, the snap fastener parts 37 and 38 can be latched. This latching imparts a stress or tension, in the longitudinal direction, to the stay 31, owing to the dimensioning of the distances "a" and "b."

The construction in accordance with the instant invention affords such tensioning of the stay substantially independently of the contents that may be disposed in the pockets or compartments of the wallet. As illustrated in Fig. 4, the stay 31 is tensioned after the snap fastener parts 37 and 38 have been latched, this illustration showing a folded wallet with only few contents and therefore of thin shape. If the wallet is "stuffed" with a large amount of bills or other objects, it will assume the thick shape shown in Fig. 5. Again, the closing of the snap fastener parts 37 and 38 will impart a tension to the stay 31. The contents inserted in the wallet have not been shown in Figs. 4 and 5 in order not to confuse the view, and only the various thicknesses of the wallet, caused by the contents, are brought out.

In order to restrain removal of the elongated portion 33 from the pocket 24, and at the same time to limit the movement of the elongated portion 33 in either longitudinal direction, there may be provided a limiting mechanism, generally indicated at 41. This mechanism comprises a longitudinal slot 42 in the elongated portion 33 and a strip 43 that is connected to the intermediate flap 23 and thereby tied to the entire right hand section composed of the right portion of the outer wall 12, the flap 16, and the intermediate flap 23. In a preferred embodiment, the strip 43 is cut out of, and integral with, the intermediate flap 23, severed therefrom by parallel cuts 44 and 46 that extend from the lower edge of the intermediate flap to points indicated at 47 above the position of the longitudinal portion 33. The strip 43 protrudes through the slot 42, and is during the manufacture of the wallet stitched or otherwise fastened to the said right hand section by the seam 17.

The slot 42, and the width of the strip 43 are so dimensioned that the ends of the slot 42 will abut against the strip 43 in the extreme positions of the stay 31. Preferably, the length of the strip 43 is so arranged that it will allow a certain play when the ends of the slot 42 reach abutment with the strip 43 in the extreme positions, so as to permit yielding through bending by the strip 43 to prevent damage to the mechanism 41. Where plastic is used for the wallet material, the resiliency of the strip 43 will enhance this yielding.

It will be apparent to those skilled in the art that the novel principles of the invention disclosed herein in connection with specific exemplifications thereof will suggest various other modifications and applications of the same.

It is, accordingly, desired that in construing the breadth of the appended claims they shall not be limited to the specific exemplifications of the invention described herein.

Having thus described the invention, what we claim as new and desire to be secured by Letters Patent, is as follows:

1. In a foldable wallet, having an outer wall, an inner wall including a flap member and a stay member associated with said outer wall and extending across at least a portion of the flap member and being movable between two extreme opposite positions transversely relative to the latter, in combination with, means for guiding and fastening said members relative to each other while permitting said movement, comprising elongated guide means on one member including a slot extending in the direction of said movement, and a resiliently yieldable elongated guide follower integral with the other member and extending therefrom and sliding in said slot to limit said movement yieldingly in either direction.

2. In a foldable wallet, comprising in combination, an outer wall folding about its midway portion, an inner wall including oppositely disposed flaps separated from each other by a gap adjacent said midway portion and forming with said outer wall pockets, and a stay extending from one flap across at least a portion of the second and being movable transversely relative thereto, said stay having a slot, and resilient means intermediate said second flap and said stay including an elongated elastic strap protruding through said slot for yieldingly confining the movement of said stay between two opposite extreme positions.
